UNITED STATES PATENT OFFICE.

EVERETT I. ROGERS, OF PROVIDENCE, RHODE ISLAND.

BUCKLE.

Application filed September 3, 1925. Serial No. 54,246.

To all whom it may concern:

Be it known that I, EVERETT I. ROGERS, a citizen of the United States, residing at 35 Orchard Ave., Providence, in the county 5 of Providence and State of Rhode Island, have invented certain new and useful Improvements in Buckles, of which the following is a specification.

My invention relates to buckles, particularly of the type having a sliding frame, 10 slideable in guideways on a main frame, having a clamping position adapted to clamp a belt end against a portion of the main frame.

15 I am aware that buckles of this general type have heretofore been constructed. The main object of my invention is to provide a buckle of this general type, the two parts of which can be readily cut and stamped out 20 of flat metal stock in a machine press with a minimum number of operations.

A further object of my invention is to provide a buckle of this type employing a minimum amount of metal, and hence on the 25 wearer a very small amount of room. Due to the specific structure of the cooperating guideways, the buckle itself is very thin, and as the sliding frame functions entirely in rear of and on the guideways, it is completely hidden from view by the main frame and the locked belt end. Due to the specific 30 construction of my guideways, the clamping portions of said frames are able to function in parallel planes very close together, thus permitting the belt to lock on a straight 35 pull though without distorting the position of the buckle on the wearer's waist.

A further object of my invention is to provide in a buckle of a type having a sliding 40 frame, slideable in rear of and on guideways mounted on a main frame, means to limit the sliding movement of the sliding frame in both directions.

These and such other objects of my invention 45 as may hereinafter appear will be best understood from a description of one embodiment thereof such as is shown in the accompanying drawings.

In the drawings, Fig. 1 is a front elevation 50 of my buckle with belt attached in operative position on the wearer's waist.

Fig. 2 is a longitudinal sectional view taken along the line 2—2 of Fig. 1.

Fig. 3 is a longitudinal sectional view 55 similar to Fig. 2 showing the belt end in the process of being inserted, and before a

straight pull on the belt end has operated to bring the clamping portions of said frames into clamped position.

Fig. 4 is a cross-sectional view taken along 60 the line 4—4 of Fig. 3, the belt end not being shown.

Fig. 5 is a rear elevation of the buckle.

Fig. 6 is a rear disassembled perspective view of the main frame and sliding frame 65 of my invention, before the sliding frame has been inserted in the guideways of the main frame, and before the stop lugs which limit the rearward movement of the sliding frame have been bent down to block the rear 70 ends of the main frame guideways.

Fig. 7 is a rear perspective view of a modified form of the main frame of my invention illustrating how the sidebars may be rectangular rather than tapered as shown 75 in my preferred embodiment.

In the drawings, wherein like characters of reference indicate like parts throughout, 80 generally indicates my invention. As stated, my invention comprises the two co-operating members which may be readily stamped from sheet metal stock with a minimum number of pressing and stamping operations. These members comprise the main frame 22 and the sliding frame 24 85 slideable thereon. The main frame 22 is preferably hollow and comprises the end bars 26 and 28 and side bars 30 preferably integrally joined together. The rear end bar 28 forms the belt attaching bar, and the 90 stationary belt end 32 may be looped around said belt attaching bar 28 and secured thereto in any suitable fashion. I employ the word "rear" to signify the direction of the fixed belt end 32 and the word "front" the 95 opposite direction. I employ the words "inner" and "outer" relative to the center of the buckle and the words, "forward" and "backward," relative to the face and back of the buckle. In my preferred embodiment, I have shown the looped end 32 of the belt secured to the main portion thereof by the snap button 33. The belt is passed around the wearer's waist, and the free end 34 thereof is adapted to be inserted 100 through the buckle 20 and firmly clamped around the wearer's waist by said buckle in a manner to be described. To mount the sliding frame 24 on the main frame 22 to permit relative sliding movement of said members, I provide the guideways 36 on said main frame. To permit

the front side of the main frame 22 to be ornamented if desired and to be of any irregular shape, as the tapered shape shown in my preferred embodiment, I preferably 5 construct the guideways 36 on the inner edges 38 of said side bars 30, thus permitting the guideways to be parallel as they have to be for proper sliding movement of the sliding member 24. The guideways 10 36 comprise the side flanges 40 projecting backwardly from the inner edges 38 of said side bars 30 and the integral lips 42 bent outwardly from said side flanges 40 offset from said side bars 30 and parallel thereto.

15 The relatively sliding frame 24 preferably comprises the side bars 44 and the clamping cross bar 46 integrally joined together. The sliding frame 24 may also be provided with the integral front tension bar 48. In my preferred embodiment, I preferably 20 forwardly incline the front edge of clamping cross bar to form the clamping surface 50 to clamp the free belt end 34 against the inner edge of the front end bar 26 of the main frame 22 on the outward movement of said sliding frame 24 as the belt end 34 is pulled outward in use on the wearer's body. To secure the sliding frame 24 to the main frame 22 in such manner as 25 to prevent lateral movement of said frames and to permit longitudinal movement thereof, I preferably provide the outer edges 52 of said sliding frame side bars 44 with co-operating slideways 54 adapted to cooperate 30 with the slideways 36 on the main frame 22. Said slideways 54 are preferably constructed as follows, the flanges 56 project integrally forwardly from the outer edges 52 of the side bars 44 of the sliding frame 24 35 and are provided at their front ends with the inwardly projecting lips 58 parallel to said side bars 44 and offset therefrom. Said inwardly projecting lips 58 are adapted to register in the guideways 36 of the main frame 22. It is thus obvious that said 40 frames 22 and 24 are secured together against lateral movement but that relative longitudinal movement of the sliding frame 24 on the main frame 22 is permitted, the 45 lips 58 registering in the guideways 36.

50 As stated, I also provide means on said frames to limit the sliding movement of said sliding frame 24 in both directions. In my preferred embodiment, I construct said means as follows. I preferably construct the front end bar 26 of the main frame 22 with a stop lip 60 projecting integrally backwardly therefrom. It is obvious that this stop lip 60 will abut the front edge 62 of the 55 sliding frame 24 to limit its outward movement. To permit insertion of the lips 58 of the sliding frame within the guideways 36 of the main frame and after insertion thereof to provide means to limit the inward 60 movement of said sliding frame 24, I prefer-

ably construct the rear ends of said offset slideway lips 42 of the main frame with the rearwardly projecting lugs 63. It is obvious that after the lips 58 of the sliding frame are inserted in the guideways 36 of 65 the main frame 22, that said lugs 63 may be bent downwards to block the rear ends of said main frame slideways 36 to limit the inward movement of said sliding frame 24. Due to the method of constructing the 70 guideways 36 on the inner edges 38 of the side bars 30 of the main frame, it is obvious that the side bars may be constructed of varying thickness and shape as shown in 75 my preferred embodiment and still permit the guideways 36 to be parallel for proper sliding of the sliding frame 24 therein. Fig. 7 illustrates an embodiment of my invention 80 wherein the outer edges 64 of the side bars 30 are also parallel as well as the inner edges 38, illustrating how the main frame 85 of my invention may be made in any number of shapes without departing from the spirit of my invention.

85 After the buckle is assembled, and the fixed belt end 32 securely attached to the belt attaching rear end bar 28, and the free end 34 of the belt looped around the wearer's body, it is inserted as shown in Fig. 3 90 from underneath the sliding member 24 in the space 66 formed between the front bar 48 of the sliding member and the clamping bar 46 thereof, the sliding member 24 having been retracted to its inmost position on the 95 slideways 36. After the free end 34 has been pulled through the space 66 to adjust the belt to the desired degree of tightness around the wearer's body, it is obvious that a straight pull on the belt will cause outward movement of the front tension end bar 48 of the sliding frame, thereby causing the clamping portion 50 of the sliding frame 24 to clamp the free belt end 34 against the inner edge 68 of the front bar 26 of the main frame, thus securely binding the free end 100 of the belt around the wearer's body.

105 It is obvious that I have provided a buckle which will firmly lock a belt around the wearer's waist on a straight pull on the belt, and which will lock tighter as the pressure 110 on the belt is increased. It is also obvious that, due to the construction of the guideways, the sliding frame is completely hidden and that it slides in rear of the main frame. It is also obvious that I have provided a construction which will accommodate 115 itself to different thicknesses of belts. I have also provided a buckle of this type thinner and made out of a smaller amount 120 of stock than any hitherto provided and in which the parts thereof function in parallel planes close together. It is also obvious that I have provided means to limit the sliding 125 of movement of the sliding member in both directions.

It is understood that my invention is not limited to the specific embodiment shown and that various deviations may be made therefrom without departing from the 5 spirit and scope of the appended claims.

What I claim as new and desire to secure by Letters Patent is:

1. A buckle, comprising a hollow main frame having end bars and side bars integrally joined together, the rear end bar forming a belt attaching bar and the inner edges of said side bars having slideways formed by flanges projecting backwardly and then outwardly to form lips parallel to 10 said side bars and offset therefrom, and a sliding frame comprising side bars, an end bar at the front end thereof and a central clamping cross bar integrally joined together, the front edge of said cross bar being 15 forwardly inclined to form a clamping surface to clamp a belt end against the inner edge of the front end bar of the main frame on outward movement on said sliding frame, the outer edges of said side bars 20 having cooperating slideways formed by flanges projecting forwardly and then inwardly to form lips parallel to said side bars and offset therefrom, said inwardly projecting lips registering in the guideways of 25 said main frame to secure said frames against lateral movement and to permit longitudinal movement of said sliding frame in rear of and on said guideways, and means on said 30 frames to limit the sliding movement of said sliding frame in both directions, comprising a stop lip projecting integrally backwardly from the front end bar of the main frame adapted to abut the front edge of said sliding frame to limit its outward movement and 35 stop lugs projecting from the rear end of said main frame slideways to limit the inward movement of said sliding frame.

2. A buckle, comprising a main frame having end bars and side bars integrally joined together, the rear end bar forming a belt attaching bar and the inner edges of said side bars having slideways formed by flanges projecting backwardly and then outwardly to form lips parallel to 40 said side bars and offset therefrom, and a sliding frame comprising side bars, an end bar at the front end thereof, and a central clamping cross bar to 45 clamp a belt end against the inner edge of the front end bar of the main frame on outward movement of said sliding frame integrally joined together, the outer edges of 50

said side bars having cooperating slideways formed by flanges projecting forwardly and then inwardly to form lips parallel to said side bars and offset therefrom, said inwardly projecting lips registering in the guide ways of said main frame to secure said frames against lateral movement and to permit longitudinal movement of said sliding frame in rear of and on said guideways and means 60 on said frames to limit the sliding movement of said sliding frames in both directions, comprising a stop lip projecting integrally backwardly from the front end bar of the main frame adapted to abut the front edge 65 of said sliding frame to limit its outward movement and stop lugs projecting from the rear ends of said offset slideway lips of the main frame to block the rear ends of said main frame slideways to limit the inward 70 movement of said sliding frame.

3. A buckle, comprising a hollow main frame having end bars and side bars integrally joined together, the rear end bar forming a belt attaching bar and the inner 80 edges of said side bars having slideways formed by flanges projecting backwardly and then outwardly to form lips parallel to said side bars and offset therefrom, and a sliding frame comprising side bars and a 85 clamping cross bar forwardly inclined to form a clamping surface to clamp a belt end against the inner edge of the front end bar of the main frame on outward movement of said sliding frame, the outer edges of said 90 side bars having cooperating slideways formed by flanges projecting forwardly and then inwardly to form lips parallel to said side bars and offset therefrom, said inwardly projecting lips registering in the guideways 95 of said main frame to secure said frames against lateral movement and to permit longitudinal movement of said sliding frame in rear of and on said guideways, and means on said 100 frames to limit the sliding movement of said sliding frame in both directions, comprising a stop lip projecting integrally backwardly from the front end bar of the main frame adapted to abut the front edge of said sliding frame to limit its outward movement and stop lugs projecting downward from the rear ends of said offset slideway lips of the main frame to block the rear ends of said main frame slideways to limit the inward movement of said sliding frame. 105

In testimony whereof I affix my signature.
EVERETT I. ROGERS.
